UNITED STATES PATENT OFFICE.

SIDNEY C. WOOD, OF BROOKLYN, NEW YORK, ASSIGNOR OF ONE-HALF TO WALLACE
E. J. COLLINS, OF HUNTINGTON, LONG ISLAND, NEW YORK.

SANITARY SYRINGE NOZZLE.

Application filed April 22, 1926. Serial No. 103,776.

This invention relates to surgical or therapeutic apparatus and has special reference to means or methods for the treatment of ailments or diseases of women.

5 Among the objects of the invention is to provide a means for the flushing or irrigation of the female generative organs that may be practiced with the highest degree of facility and expedition as well as personal 10 comfort, and that will perform its functions in the most reliable and efficient manner, with respect to maximum cleanliness, sanitation, and remedial efficacy.

With the foregoing and other objects in view the invention consists in the arrangement and combination of parts hereinafter described and claimed, and while the invention is not restricted to the exact details of construction disclosed or suggested herein, 20 still for the purpose of illustrating a practical embodiment thereof reference is had to the accompanying drawings, in which like reference characters designate the same parts in the several views, and in which—

25 Figure 1 is a perspective view of a preferred embodiment of the invention.

Fig. 2 is a longitudinal section of the nozzle and associated parts.

Fig. 3 is a transverse sectional detail on the line 3—3 of Fig. 2.

Referring now more specifically to the drawings, I show an apparatus comprising a nozzle 10 of peculiar design and construction, the same being so shaped as to be applied and manipulated most easily, comfortably, and effectively. The nozzle may be described in general terms as consisting of a conical member, of arcuate form, or with its point portion bent upward from the axis of the base portion, or at an oblique angle to the plane of the base portion. In the consideration of this description it will be borne in mind that two important objects are aimed at and which I have provided for most effectively,—maximum penetration or insertion of the cleansing or medicated fluid and the retention thereof in the largest volume consistent with the internal capacity of the organ being treated.

50 The nozzle 10 includes a base portion consisting of a hollow body 11, of elliptical form in cross section, and, having imperforate flexible side walls and being approxi-

mately in the form of a frustum of an oblique cone and having a nearly flat base 65 flange 12 of elliptical form. The flange has its side edge 12^a inclined upwardly from the flat plane of the flange as a base in a substantially frusto-conical form, and said surface 12^a is preferably of somewhat arcuate form 60 for the sake of maximum ease of operation of the device. A hollow or channel 12^b of annular form extends along the periphery of the flange 12 upon that side thereof remote from the flat plane of the flange as 65 aforesaid providing a sealing lip 12^c. This combined with the fact that the thickness of the flange 12 diminishes considerably toward the shorter axis of the elliptical flange 12 as shown at 12^d, insures of the most effective fitting of the device to the female generative organ when the stem is inserted to its full extent, and consequently of the most reliable sealing of said organ. The upper surface of the flange, or that side of the flange 70 which is nearest the stem 12 is thus seen to be generally of hollowed or concave formation and to have an effective peripheral sealing lip which lies in an arcuate surface.

The upward extension from the hollow 80 flexible body 11 is a stem 13, which though made preferably as an integral and homogeneous part of the body is materially stiffer than the body and terminates in a rounded point 14. An axial port 15 extends along 85 the center of the stem for delivery of the fluid to and through a series of lateral or radial ports 16 at or near the point 14 which communicate with longitudinal distribution ducts 17 along the outside of the point portion 90 14.

Within the body 11 and constituting in effect an integral extension of the mass of the stem portion 13 is a nipple 18 having a bore or axial port 19 in direct communication with the port 15. The parts thus far described may be thought of being formed, as by molding, as of one piece of material such as vulcanized rubber and hence of a flexible or elastic nature and hence self conformable to the anatomy of each patient. The stem 13 because it is more nearly solid is naturally stiffer than the body 11 and so is more conducive to direct and easy penetration. The body 11, because of its relatively flexible or pliable nature is calculated to 100 105

be projected into the organ being treated so that the base flange 12 will fit close against or around the opening of the tissues, the body 11 and base 12 co-operating 5 to serve as a plug or closure for the organ, so as to insure maximum expansion or dilation of the complex folds or internal tissues to be reached for medication or cleansing. From the composition and structure of the 10 nozzle, moreover, it may readily and thoroughly be sterilized after each use or application in practice.

At 20 I indicate a suggestion of any suitable container, reservoir, or source of supply or means to provide an application of a sterilizing or medicated fluid to and through the nozzle. A tube 21 conveys the fluid from its source to the nipple 18 with which the tube is detachably connected, as through 15 a tubular coupling 22 of hard rubber, or its equivalent, projected into the axial port 19, the outer end 23 of said coupling being internally threaded to receive the threaded end 24 of a coupling 25 having an end with 20 which the tube 21 is connected. It will be understood that the coupling 22 is intended to remain permanently in engagement with the nipple 18. By means of this arrangement, a reliable connection is provided between 25 the tube 21 and the nipple 18, which connection can be broken with ease and celerity, and interchangeability is provided for. That neck portion of the nipple between the coupling and the main part of the 30 stem is flexible and hence the tubular connection may take any direction or angle within the hollow body, according to the position or anatomical condition of the patient and the location or elevation of the 35 source 20.

An essential feature of my invention resides in the provision of novel draining means whereby the cleansing fluid can be removed with the greatest convenience. 40 Thus I provide a hollow or channel 26 extending lengthwise of the stem 13 and along the bottom thereof relative to the normal direction of use of the instrument in the female generative organ. A nipple 27 of hard 45 rubber or the like is extended through flange 12 so as to communicate with the channel 26. A rubber tube having a pinch cock may be connected to said nipple, but this being conventional is not shown in the drawings. 50 By manipulation of the pinch cock, the cleansing fluid may be drained as desired, and the fluid may be retained in the organ as may be found suitable or necessary. 55 Since the drainage channel 26 is at the outside of the nozzle, said channel can be cleaned with the greatest ease. The outlet of the 60 open channel at nipple 27 is well within the organ sealing means. Moreover, drainage can be accomplished with the maximum 65 effectiveness, since the channel 26 extends

along the extreme underside of the nozzle. Simplicity of construction is likewise maintained.

From the foregoing specific description of the apparatus, a brief resumé of its use 70 and operation should suffice. With the patient in a reclining position on her back, or sitting more or less erect, the point 14 will be projected inward and upward, the longer axis of the elliptical base 12 and body 11 75 being upright, and the base will be forced with a moderate degree of pressure sufficiently far inward for the flanged base portion to seal substantially the mouth of the organ. The resilient walls of the body 11 80 readily and comfortably conform at this time to both the size and shape of the adjacent tissues. While the nozzle is held in this position, with the point portion 14 well upward on the interior, the medicament or sterilizing fluid will be introduced through the channels and ports described. As a result of the described construction and close fitting application of the base portion to the anatomy, as set forth, the fluid will or 85 may be retained within the organ and, with sufficient pressure at the source, will distend or balloon the tissues and so reach into or between all the intricate and complex interstices, where it is impossible for such fluids 90 to reach under other commonly practiced methods. After being so retained under sufficient distending pressure as long as required or desired, the fluid will be permitted to drain away, preferably through channel 95 26 and nipple 27 to any suitable receptacle by means of a rubber tube or the like as may be found convenient.

I claim:

1. The herein described douche comprising a nozzle, and means including a base flange projecting from and surrounding said nozzle, the flange being arranged to seal an organ into which the nozzle is inserted, the flange being provided for this purpose with an annular channel on that side of the flange nearest the nozzle, the outer edge of the channel constituting an annular sealing lip projecting generally toward the nozzle for effective sealing of the organ as aforesaid, said flange being of relatively considerable thickness for the sake of requisite stiffness, and having an edge surface of substantially frusto-conical form, the smaller base whereof is on that side of the flange nearest the nozzle, the face of the flange remote from said nozzle providing an acute angle sealing edge.

2. The herein described douche comprising a nozzle, and means including a base flange projecting from and surrounding said nozzle, the flange being arranged to seal an organ into which the nozzle is inserted, the flange being provided for this purpose with an annular channel on that side of the flange 120 125 130

nearest the nozzle, the outer edge of the channel constituting an annular sealing lip projecting generally toward the nozzle for effective sealing of the organ as aforesaid, the 5 flange being of elliptical form, the axis of the nozzle lying in the plane of the longer axis of the flange, the flange being of a maximum thickness at the ends of said longer axis

and decreasing in thickness toward the region at the ends of the shorter axis of the 10 flange thus providing for flexibility about the shorter axis of the flange, said sealing lip lying therefore in an arcuate surface.

In testimony whereof I affix my signature.

SIDNEY C. WOOD.
